UNITED STATES PATENT OFFICE.

WILBERFORCE BEECHER HAMMOND, OF BOSTON, MASSACHUSETTS, ASSIGNEE, BY
MESNE ASSIGNMENTS, TO COMBINED HEAT AND SPRINKLER COMPANY, A COR-
PORATION OF MASSACHUSETTS.

AUTOMATIC SPRINKLER.

1,228,553.

Specification of Letters Patent. Patented June 5, 1917.

Application filed October 19, 1915. Serial No. 56,781.

To all whom it may concern:

Be it known that I, WILBERFORCE BEECHER HAMMOND, citizen of the United States, and resident of Boston, in the county of Suffolk and State of Massachusetts, have invented new and useful Improvements in Automatic Sprinklers, of which the following is a specification.

This invention relates to automatic sprinklers, and its object is to provide a novel and effective sprinkler head, to be connected to the piping of a hot water heating system, and so constructed that the heat-sensitive fusible member will be kept at a safely low temperature notwithstanding that the sprinkler head itself is intimately connected with a piping system in which the water is at a temperature higher than that designed to soften the sensitive element and release the sprinkler. The invention consists further in the novel, effective and economical construction of the toggle-lever members hereinafter described.

In the accompanying drawings which illustrate the invention,—

Figure 1 shows a sprinkler head partly in side elevation and partly in section;

Fig. 2 is a perspective view of one of the toggle-lever members;

Fig. 3 is a perspective view of the other toggle-lever member;

Fig. 4 is a detail in side elevation illustrating a modification;

Fig. 5 is a perspective view of one of the toggle-lever members shown in Fig. 4; and

Fig. 6 is a perspective view of the other toggle-lever member shown in Fig. 4.

The type of sprinkler head used for the purpose of illustration is the Grinnell sprinkler, but the invention is also applicable to other types of sprinklers employing toggle systems held under restraint by the heat sensitive fusible member which is characteristic of all such sprinkler heads.

Referring to Figs. 1, 2 and 3 of the drawings, A is the base of the sprinkler head, which is connected to the piping of the hot water heating system. B is the frame, C is the valve, and D is the abutment for the toggle members opposite the valve. These parts may be of any usual or preferred construction.

The valve C is normally held firmly

pressed upon its seat by the toggle-lever members T¹, T² which are held in position by their lever arms and a heat sensitive fusible link. Said toggle-lever members are preferably made of sheet material, the blanks for which are stamped out and then bent into the forms shown.

The member T¹ is bent to form the short toggle part t¹ and the lever supporting part t¹' arranged at an angle to each other to provide a shoulder t² for engaging and holding the end of the other member T². The lever arm t² is bent up from one side of the part t¹ at a slightly acute angle thereto.

The other toggle-lever member consists of the relatively long toggle part t² and the lever arm t²', bent up from the side of part t² at a slightly acute angle thereto.

The acute angled bends of the lever arms bring the two notches n and n', which hold the fusible link into substantially the same plane as the toggle points p, p' thus avoiding any twisting strain when the parts are assembled.

The sensitive link E may be of usual construction, and as herein shown consists of two plates of copper or other suitable material, soldered together with some readily fusible metal.

The arms t¹ and t² are preferably provided with perforations or otherwise made of openwork structure, to provide relatively large radiating surfaces, and small cross sections, so that the heat conducted from the hot water piping system and through the sprinkler head will be dissipated before reaching the sensitive fusible member E.

Instead of retaining the toggle-lever members in position by a link E under tension to prevent the release of the sprinkler head by swinging the arms apart, the toggle-lever members may be so constructed as to release the sprinkler head by the swinging of the arms toward each other, in which case they will be retained in position by a heat sensitive strut. Such modification is illustrated in Figs. 4 and 6, wherein one toggle-lever member T¹ has the short toggle part t¹, the lever supporting part t¹' arranged at an angle to form a shoulder t¹', and the lever arm t¹' bent up at a slightly acute angle to the part t¹.

The other toggle-lever member consists of

the relatively long toggle part t^{10} , and the lever arm t^{11} bent up from the part t^{10} at a slightly acute angle.

A strut E' , of any suitable construction 5 adapted to collapse in the presence of heat, engages notches in the lever arms t^9 and t^{11} to hold the toggle-lever members in operative position.

I claim:

- 10 1. In an automatic sprinkler of the character described, a pair of valve holding toggle lever members, each integrally formed of sheet metal, one bent to form a relatively short toggle portion, an arm supporting portion bent at an angle to said toggle portion, and a laterally extending lever arm bent up from one side of said arm supporting portion, and the other member bent to form a relatively long toggle portion, which en-
- 15

gages said shoulder, and a lever arm extending from one side of said toggle portion. 20

2. In an automatic sprinkler of the character described, a pair of valve holding toggle-lever members, each integrally formed of sheet metal, one bent to form a relatively short toggle portion, an arm supporting portion bent at an angle to said toggle portion, and a laterally extending lever arm bent up from one side of said arm supporting portion, and the other member bent to form a relatively long toggle portion, which engages said shoulder, and a lever arm extending from one side of said toggle portion, both of said lever arms being perforated to provide an open work and heat dispersing structure. 25 30 35

Signed by me at Boston, Massachusetts, this 16th day of October, 1915.

WILBERFORCE BEECHER HAMMOND.
